T. BARTHOLOMEW & F. SCHULTZ.
BUGGY BOOT CLOSURE.
APPLICATION FILED JULY 26, 1905.

UNITED STATES PATENT OFFICE.

THOMAS BARTHOLOMEW AND FRANK SCHULTZ, OF BASIL, OHIO.

BUGGY-BOOT CLOSURE.

No. 828,082.

Specification of Letters Patent.

Patented Aug. 7, 1906.

Application filed July 26, 1905. Serial No. 271,360.

To all whom it may concern:

Be it known that we, THOMAS BARTHOLOMEW and FRANK SCHULTZ, citizens of the United States, residing at Basil, in the county of Fairfield and State of Ohio, have invented new and useful Improvements in Buggy-Boot Closures, of which the following is a specification.

In vehicles of certain types the body or box is commonly closed in the rear of the seat by a board or leather top, often called a "boot," detachably secured in such manner that it may be raised to permit access to the interior of the box. To provide for thus closing a vehicle-box by devices that are easily attached even after the vehicle is in use, that hold the box open when it has been opened and when it is closed hold it so firmly closed that there is neither rattling nor wear, and that permit opening or closing as quickly as if no such devices were present are objects of our invention.

In the accompanying drawings, Figure 1 is a side elevation of a vehicle-body provided with our devices, the boot being open and parts being broken away. Fig. 2 is a similar view, the boot being closed. Fig. 3 is an enlarged plan view of the boot-securing devices. Fig. 4 is a side elevation of the parts seen in Fig. 3. Figs. 5 and 6 are respectively an elevation and a plan view showing a modified construction.

In the drawings, A represents a buggy-body of the "piano-box" type, and B a leather boot having the usual light skeleton frame C, covered with leather, which in this instance extends forward from the frame and is secured at D beneath the seat to form a hinge for the boot. The boot-frame is of such form as to fit the upper edge of the box from the seat rearward, so that the boot as a whole may form a neat and effectual closure for this portion of the box, excluding dust and concealing any articles that may be placed therein.

Beneath the seat there is shown in this instance a cross-bar E, forming a part of the body, and to this is fixed a horizontal rearwardly-projecting double post F, having its branches forked to form bearings for an arm G, which extends rearward and is attached to the rear side of the boot. The forward end of the arm has two branches which fit between the branches of the post and are provided with short pivotal studs H, lying in the

forked branches of the post, respectively, and about these studs the arm swings as the boot is opened and closed. As the axes of rotation of the arm and of the boot are not coincident, the point of the arm's attachment to the boot does not remain at a fixed distance from the pivots H, and therefore the arm is made readily extensible by providing a part G' to slide in a tubular rear portion G², which has at its rear end a flat plate of pliable metal provided with a lip G³, stamped up to engage the forward edge of the rear member of the boot-frame, about whose rear edge the plate is bent upward, thus firmly attaching the arm without the use of tools.

The arm-pivots being above the rear end of the box, the arm normally extends obliquely downward and rearward and then horizontally just below the boot to the point of attachment, which is at the rear end of the boot and box. A spring-coil J, normally under tension, lies between the branches of the post and arm and is attached to the base of the post at F approximately in the horizontal plane of the pivots H and at the other end is secured to the arm at a point J' normally below the plane of the pivots. The spring, which is preferably a strong one, thus normally subtends the angle formed by the post and arm and tends to decrease that angle, or, in other words, it pulls the arm downward and presses the rear end of the boot very firmly down upon the box. If the boot be forcibly lifted to the position of Fig. 1, the spring swings upward until the line of its strain crosses the pivotal axis, after which the spring tends to swing the boot still farther open. The opening is limited, however, by providing at least one of the pivots H with a wing H', which strikes the upper wall of the corresponding fork of the post and prevents farther advance of the arm. Thus the boot, which may be opened and closed as quickly as it could be if simply hinged, is held open when opened and when closed is pressed down so strongly that practically no wear nor rattling can occur. The pressure, although very considerable, is exerted at the rear side of the frame, and hence the frame may be made very light, so that it is but slightly acted upon by sudden movements of the body, its possible momentum being trifling. Were the rear side of the boot to be pressed down with equal force transmitted by the frame itself the frame would obviously

need to be much heavier. It may be noted also that the devices may be easily attached to any buggy of proper form without marring any visible part in the least and without the use of tools other than a screw-driver.

Figs. 5 and 6 show two bars J J', pivoted together or jointed at J' and further connected by a spring-coil L, secured to the bars at some distance from the pivotal point and always 10 tending to resist the approach of the bars to a straight line. This device is similar in principle to the better form shown in the other figures as a forked post and forked arm, and if it be properly connected to the parts it will 15 also hold the boot open or closed, as the case may be.

What we claim is—

1. The combination with a bracket adapted to be fixed beneath the seat of a buggy, of 20 a laterally-rigid, extensible arm hinged to said bracket to swing vertically and having its free end adapted for attachment to the rear side of a buggy-boot.

2. The combination with the vehicle-body 25 and the boot hinged near the rear side of the seat, of the double post fixed below the boot's axis of rotation, the forked arm pivoted at one end to the post and at the other engaging the free side of the boot, and the spring normally 30 under tension and connecting a point near the base of the post to a point upon said

arm normally below the horizontal plane of the arm's pivot.

3. As a new article of manufacture, a buggy-boot-closing device comprising a post 35 adapted to be fixed to the body beneath the seat, an arm pivotally connected with said post and at its rear end consisting of thin pliable metal adapted to engage the rear member of a boot by simple bending, and a spring 40 tending to decrease the angle made by said post and arm.

4. The combination with a bracket adapted to be fixed beneath a buggy-seat, above the body and midway between the planes of 45 its sides, of an arm hinged to said bracket to swing vertically, composed of two telescoping segments, and having its free end adapted for attachment to the rear edge of a buggy-boot, and a spring connecting said bracket 50 and arm and arranged to swing from side to side of the arm's pivot when the arm swings as in opening and closing the boot.

In testimony whereof we affix our signatures in presence of two subscribing witnesses.
